UNITED STATES PATENT OFFICE.

ARCHIBALD R. STEPHEN, OF LODI, CALIFORNIA.

BEATER ADJUSTMENT FOR ALMOND HULLERS.

1,405,726.

Specification of Letters Patent. Patented Feb. 7, 1922.

Application filed April 12, 1921. Serial No. 480,733.

To all whom it may concern:

Be it known that I, ARCHIBALD R. STEPHEN, a citizen of the United States, residing at Lodi, county of San Joaquin, State 5 of California, have invented certain new and useful Improvements in Beater Adjustments for Almond Hullers; and I do declare the following to be a full, clear, and exact description of the same, reference being had to 10 the accompanying drawings, and to the characters of reference marked thereon, which form a part of this application.

This invention relates to improvements in adjustment means for the beaters of almond 15 hulling machines, being particularly intended to be used with that type of huller shown in my Patent No. 1,359,766, dated November 23rd, 1920. This machine has a drum, a concentric driving shaft therein, and a plurality of radially and longitudinally disposed beater boards mounted in driving relation with the shaft.

It is highly desirable and in fact necessary to be able to adjust the beaters relative to 25 their spacing from the periphery of the drum, in order to insure proper and efficient hulling or cracking of almonds of different sizes. Such adjustment should also be made to all the beaters simultaneously or in unison 30 for obvious reasons.

My previous patent shows such an adjustment means, but operable from the interior of the drum. This necessitates removing the cover from the drum, making an adjustment 35 and replacing the cover to try out the new adjustment, very often having to repeat the operation, since the correct adjustment with this type is somewhat a matter of guess-work.

40 The principal object of the present invention therefore is to eliminate considerable of the time and labor necessary with the above described construction, by providing a means for adjusting the beaters from the 45 exterior of the drum.

Another and also important object is to provide a gage means whereby the amount the unseen beaters are moved may be positively and accurately determined, and since 50 the operator knows what size almonds the machine is about to handle, and also knows from experience the necessary spacing of the beaters from the drum to give proper results with certain sized nuts, the adjustments can be easily and quickly made, with 55 the assurance that the beaters are correctly

positioned without any guesswork or try-outs entering into the operation.

A further object of the invention is to produce a simple and inexpensive device 60 and yet one which will be exceedingly effective for the purposes which it is designed.

These objects I accomplish by means of such structure and relative arrangement of 65 parts as will fully appear by a perusal of the following specification and claims.

In the drawings similar characters of reference indicate corresponding parts in the several views.

Fig. 1 is a sectional elevation of my huller, 70 showing the improved beater adjustment means installed in connection therewith.

Fig. 2 is an enlarged sectional view of the adjustment mechanism itself.

Fig. 3 is a fragmentary section taken on a line 3-3 of Fig. 2.

Fig. 4 is a similar view taken on a line 4-4 of Fig. 3.

Referring now more particularly to the 80 characters of reference on the drawings, the numeral 1 denotes a stationary drum of any suitable construction, projecting through which is a hollow shaft 2 journaled in exterior bearings 3 and adapted to be rotated 85 by any suitable means as for instance through the medium of a pulley 4.

Fixed on the shaft inside the drum are radial arms 5, at the outer ends of which the beater boards 6 are slidably mounted 90 for radial adjustment.

Fixed on the boards and positioned along side the arms 5 and parallel thereto are angle irons 7, which not only serve to strengthen and brace the boards, the latter 95 being of wood, but prevent undue longitudinal movement of the boards relative to the arms.

My improved beater-adjustment mechanism is constructed as follows:

Turnably mounted in the sleeve-shaft 2, but held against relative longitudinal movement is a shaft 8, preferably formed in two lengths suitably and rigidly coupled together, as shown at 9, this construction being 105 merely for ease of manufacture and assembly.

On each side of the coupling the shaft is threaded, one portion of such being right hand and the other left hand, as shown at 10 and 11 respectively. Threaded onto such portions are sleeves 12 provided with op-

- posed and radially disposed arms 13 which project through and are slideable in slots 14 cut in the sleeve 2 for a certain distance in the length thereof. Slidable on the sleeve 2 are hubs 15 from which a plurality of arms 16 project radially, the number of such arms being the same as the number of beater boards employed. The arms 13 and hubs 15 are rigidly connected together by clamp-bolts 17, so that for all practical purposes the corresponding members 12 to 15 can be considered as a unit, the above construction being used as being the most practical to make under the circumstances.
- 15 The outer ends of the arms 16 are flexibly connected to the beater boards by adjustable links 16^a, which extend away from each other toward their outer ends, the adjustability of the links being for the purpose of correctly 20 alining the beater boards relative to the drive shaft when first setting up the machine.

On one end of the shaft 8, to turn the same, is a hand wheel 18, having a graduated scale-shaft 19 projecting parallel to and extending along the sleeve 2. This scale member is slideable between the lugs 20 of a sleeve or collar 21 threaded on the sleeve 2, the number of threads per inch on the latter 30 being the same as that of the threaded portions 10 and 11 of the shaft 8.

A lock nut 22 adapted to bind and clamp the collar in place is also mounted on the sleeve 2 adjacent said collar.

35 Movement of the collar 21 is limited in one direction by a cap 23 on the outer end of the sleeve 2 and in the other direction by a stop 24 on the member 19, so that the movement of the beaters is correspondingly 40 limited, the range of possible movement being determined to take care of all adjustments which may be necessary.

The operation of the adjustment mechanism is as follows:

45 The main shaft 2 is first stopped from rotation, and the lock nut 22 then backed away from the collar 21. The hand wheel 18 may then be rotated which turns the shaft 8 and causes the members 15 to be moved 50 in opposite directions therewith, thus either straightening the links 16^a and causing the beater boards to lie closer to the drum, or increasing the angle of the links and drawing the boards inwardly, depending on the 55 direction of rotation of the wheel.

At the same time, the scale or gage pin rotates with the wheel, and this member, bearing against the collar-lugs, causes the latter to move along the sleeve 2 owing to its 60 threaded connection therewith, the distance thus moved lengthwise of said sleeve and the gage pin being the same distance as each member 15 moves.

The lugs 20 co-act with the graduations 65 on the gage member so that they form a

marker to determine and control the amount of movement had or desired, each inch of graduation on the scale representing a pre-determined and always proportional radial movement of the beaters, so that the position 70 of the beaters may be gaged to a nicety.

When the adjusting operation is completed, the lock nut is clamped against the collar, and the sleeve 2 may then be rotated, the entire adjustment structure rotating 75 therewith as a unit.

During the operation of the machine, no strain is taken by this mechanism, since the load, using this word in its technical sense, is carried by the arms 5 and the 80 shaft 20.

From the foregoing description it will be readily seen that I have produced such a device as substantially fulfills the objects 85 of the invention as set forth herein.

While this specification sets forth in detail the present and preferred construction of the device, still in practice such deviations from such detail may be resorted to and do not form a departure from the spirit of the invention, as defined by the appended claims.

Having thus described my invention, what I claim as new and useful and desire to secure by Letters Patent is:

1. In an almond huller comprising a drum, 95 a driven shaft passing therethrough, beater boards mounted in connection with said shaft and arranged for radial movement relative thereto, sleeves slidably mounted on the shaft and turnable therewith, means connecting said sleeves with the beater boards whereby said boards will have radial movement imparted thereto when the sleeves are moved in opposite directions, a shaft adapted to be turned by hand from one end 100 of the first named shaft and extending therethrough, and means operatively connecting said hand turned shaft with the sleeves to move the latter in opposite directions with the rotation of said latter shaft.

2. In an almond huller comprising a drum, a driven shaft passing therethrough, beater boards mounted in connection with said shaft and arranged for radial movement relative thereto, sleeves slidably mounted on the shaft and turnable therewith, means connecting said sleeves with the beater boards whereby said boards will have radial movement imparted thereto when the sleeves are moved in opposite directions, a shaft 115 adapted to be turned by hand from one end of the first named shaft and extending therethrough, means operatively connecting said hand turned shaft with the sleeves to move the latter in opposite directions with the rotation of said latter shaft, and visible gage means operatively connected with said hand turned shaft whereby to indicate the radial distance moved by the boards with the rotation of said shaft. 120

3. In an almond huller comprising a drum, a driven shaft projecting therethrough, beater boards mounted in connection with said shaft and extending parallel thereto and arranged for radial movement, a pair of sleeves slidably mounted on the shaft and turnable therewith, flexible links connecting said sleeves with the beater boards and arranged to impart radial movement thereto when the sleeves are moved in opposite directions, means for so moving the sleeves from the exterior of the drum, and gage means for denoting the distance the sleeves are moved.
4. In an almond huller comprising a drum, a driven shaft projecting therethrough, beater boards mounted in connection with said shaft and arranged for radial movement relative thereto, a pair of sleeves slidably mounted on the shaft and turnable therewith, means connecting said sleeves with the beater boards whereby said boards will have radial movement imparted thereto when the sleeves are moved in opposite directions, a shaft adapted to be turned by hand from one end of the first named shaft extending therethrough, said first named shaft being hollow, similar but oppositely threaded portions on the last named shaft, and sleeves threaded onto said portions and connected to the first named sleeves, the hollow shaft being slotted longitudinally to allow of such connections being made.
5. In an almond huller comprising a drum, a driven shaft projecting therethrough, beater boards mounted in connection with said shaft and arranged for radial movement relative thereto, a pair of sleeves slidably mounted on the shaft and turnable therewith, means connecting said sleeves with the beater boards whereby said boards will have radial movement imparted thereto when the sleeves are moved in opposite directions, a shaft adapted to be turned by hand from one end of the first named shaft extending therethrough, said first named shaft being hollow, similar but oppositely threaded portions on the last named shaft, and sleeves threaded onto said portions and connected to the first named sleeves, the hollow shaft being slotted longitudinally to allow of such connections being made, a graduated scale-pin fixed on the wheel and projecting parallel to the outer shaft and alongside the same, a collar threaded on said outer shaft, lugs on said collar engaging the pin and between which the latter is slid able, the lugs serving as markers co-acting with the scale graduations, and means whereby the actual longitudinal distance traversed by said collar with the rotation of the hand wheel will be the same as that moved by each sleeve.
6. In an almond huller comprising a drum, a driven shaft projecting therethrough, beater boards mounted in connection with said shaft and arranged for radial movement relative thereto, a pair of sleeves slidably mounted on the shaft and turnable therewith, means connecting said sleeves with the beater boards whereby said boards will have radial movement imparted thereto when the sleeves are moved in opposite directions, a shaft adapted to be turned by hand from one end of the first named shaft extending therethrough, said first named shaft being hollow, similar but oppositely threaded portions on the last named shaft, and sleeves threaded onto said portions and connected to the first named sleeves, the hollow shaft being slotted longitudinally to allow of such connections being made, a graduated scale-pin fixed on the wheel and projecting parallel to the outer shaft and alongside the same, a collar threaded on said outer shaft and lugs on said collar engaging the pin and between which the latter is slid able, the lugs serving as markers co-acting with the scale graduations, and means whereby the actual longitudinal distance traversed by said collar with the rotation of the hand wheel will be the same as that moved by each sleeve.
7. In an almond huller comprising a drum, a driven shaft projecting therethrough, beater boards mounted in connection with said shaft and arranged for radial movement relative thereto, a pair of sleeves slidably mounted on the shaft and turnable therewith, means connecting said sleeves with the beater boards whereby said boards will have radial movement imparted thereto when the sleeves are moved in opposite directions, a shaft adapted to be turned by hand from one end of the first named shaft extending therethrough, said first named shaft being hollow, similar but oppositely threaded portions on the last named shaft, and sleeves threaded onto said portions and connected to the first named sleeves, the hollow shaft being slotted longitudinally to allow of such connections being made, a graduated scale-pin fixed on the wheel and projecting parallel to the outer shaft and alongside the same, a collar threaded on said outer shaft and lugs on said collar engaging the pin and between which the latter is slid able, the lugs serving as markers co-acting with the scale graduations, and means whereby the actual longitudinal distance traversed by said collar with the rotation of the hand wheel will be the same as that moved by each sleeve.
8. In an almond huller, a driven shaft, radially positioned spider-arms fixed thereto, beater boards mounted at the outer ends of the arms and arranged for relative radial play, and angle irons fixed to said boards and extending parallel to and adjacent the arms.
9. In an almond huller, a driven shaft, radially positioned spider-arms fixed thereto, beater boards mounted at the outer ends of the arms and arranged for relative radial play, adjustment means for moving all the beaters radially, and means for individually adjusting the beaters to insure their parallel alignment with the shaft.

In testimony whereof I affix my signature.
ARCHIBALD R. STEPHEN.
